PERIODICALLY ACTING SPARK GENERATING TOY

Georg Einfalt, Nuremberg, Germany, assignor to
 Transatlantic Factors, Inc., New York, N. Y., a
 corporation of New York

Application May 25, 1937, Serial No. 144,629
 In Germany December 2, 1935

15 Claims. (Cl. 46—10)

This invention relates to a periodically acting spark generating device for use in connection with toys. The primary object is to generally improve such devices. A more specific object is to produce an approximately disk-shaped spark-sheaf located about perpendicularly with respect to the axis of a piece of cerium-iron stone and a spark producing member co-operating therewith.

10 The object in view is attained chiefly thereby that the end of a spark-rod or the like is pressed against said cerium-iron stone by means of a helical spring or the like, the said stone being arranged co-axially with said rod, which is periodically quickly rotated, the resulting friction causing the production of a spark-sheaf located about perpendicularly relatively to the axis of the said rod and the said stone of cerium-iron. Other characteristic features of the invention will 15 be dealt with in the following part of this specification in connection with the drawing which shows diagrammatically and by way of example a constructional form of a device designed according to this invention. In the drawing:

20 Figure 1 is a side-view of the device used in connection with a toy-wheelwork;

Figure 2 is a plan view of the arrangement and combination of parts shown in Fig. 1;

25 Figure 3 shows the left-hand end of Fig. 2 partly in axial section and drawn to an enlarged scale;

Figure 4 shows members located right-hand from Fig. 3, likewise drawn to an enlarged scale, these members being located above the wheel-work visible in Fig. 1.

The wheel-work is held in a frame *a* which is enclosed in a casing *b* that is so shaped as to fit into the bottom-portion of a figure or a vehicle or the like. *c* denotes the spring of the wheel-work and *d* the axle or winding stem of the same. The axle projects downwardly beyond the spring, where a key may be applied to the squared end so that the wheel-work can be wound up, and above the spring there is affixed to said axle a cog-wheel *e* meshing with a pinion *f* secured to a vertical intermediate shaft *g*. The upper end and the lower end of this shaft respectively project above and below the adjacent parts of the frame, and to the upper end is affixed a crown-wheel *h*, and to the lower end a crown wheel *i*. These crown wheels are mutilated, each having teeth only on a part of the circumference, as appears distinctly from Fig. 1. The teeth of the lower crown-wheel *i* can mesh with a pinion *k* which is secured to an axle *l* constituting a running axle, and being

provided with spur-wheels *m* by means of which the device can be moved. In order to hold the device in proper position (for instance like a gun), there is attached to the rear end of the casing *b* a ball-shaped member *n* which may have, however, any other shape.

The upper crown-wheel *h* engages a pinion *p* secured to a rod *o* which will be termed the "spark-rod" in the further course of this specification. The spark-rod extends beyond the frame and the casing in a direction opposite to the part holding the supporting member *n* and is supported in brackets *q* and *r* extending upwardly from said frame. From the bracket *r* extends forwardly a tube *s* which surrounds the corresponding part of the spark rod and is closed at its free front end by a small disk *t*. (Figs. 1 and 3.) Near this disk the tube *s* is provided with a plurality of apertures *u* located just at the end of the spark rod *o*. This end is cut away or recessed at *v* (Fig. 3), the recesses transforming said end into a sort of a chisel or fork having an edge or two pointed spikes, and these spikes are located near the end of the tube *s* (Figs. 1 and 3). The spikes can be pressed against said piece *w* by means of a helical pull spring *x* encompassing the spark-rod and being located between the bracket *r* and the pinion *p*. When the spark-rod is abruptly rotated by means of the wheel-work the spikes rub on the cerium-iron and sparks are generated which then pass outwards through the apertures *u*. The left-hand end of the spring *x* is affixed to the bracket *r* and the other end is connected with the spark-rod near the pinion *p* by particularly small-diameter windings; the inner diameter of the main portion *x* of the spring is somewhat larger than the outer diameter of the spark-rod so that no jamming friction can arise between these two members, the only contact being at the part *y* where the spring is wound directly around and in frictional contact with the rod.

When the spring of the wheel-work has been wound up, the cog-wheel *e* will rotate the pinion *f* and this will turn the crown-wheels *h* and *i*, the teeth of which are arranged out of step, preferably on diametrically opposite sides, as appears from Fig. 1. The lower crown-wheel will transmit the motion to the running wheels *m* by the intermediary of the members *i*, *k*, *l* whereby the device will be moved as long as the wheels *i* and *k* mesh with one another, say, for half of each revolution. The upper crown-wheel (*h*) rotates the pinion *p* which now turns the spark-rod *o*, the spikes or chisel edge of which rub on the cerium-iron piece *w*. The normal smooth for-

ward movement of the rod does not produce a shower of sparks, but upon abrupt movements there is generated the sparks which rush outwardly through the apertures *u* forming in their entirety a spark-sheaf, as indicated at the left-hand end of Fig. 1.

The action of the spring *x* is peculiar. When the spark rod *o* is turned by the members *h* and *p* while the device is being moved forwardly by the 10 running wheels *m* etc., the convolutions of the spring are wound up and contracted, viz., radially inwardly. The spikes of the spark rod are pressed against the cerium-iron piece *w*. This lasts as long as the gears are in mesh and the spark rod 15 is running forwardly, but when the crown-wheel *h* gets out of mesh with the pinion *p*, the tension of the spring *x* is relieved and spring *x* abruptly unwinds, causing a sudden reverse rotation of the rod *o*. This produces a shower of 20 sparks. At the same time the crown-wheel *i* has left the pinion *k*, in consequence whereof the device comes to a standstill and remains so until these members (*i* and *k*) mesh again with one another. Then after the dwell in forward movement with the accompanying flash of sparks during 25 the dwell, the members *h* and *p* will again mesh with one another, and the entire cycle of operation will be repeated, and so on.

The entire device may be housed, for instance, 30 in the hollow figure of a seemingly creeping rifleman who fires his gun intermittently and creeps intermittently forwards. The creeping motion stops during the firing period. In order to make the procedure appear more natural, the running 35 wheels may be eccentric so as to make the rifleman rise and lower slightly, as would in reality be the case. It is as well possible to mount the device in an armored motor-car or the like.

I claim:

1. A periodically acting spark-producing device for use in connection with toys, comprising, in combination, a sparking rod, a piece of cerium-iron arranged co-axially with said rod, means for pressing the rod against said piece of cerium-iron, 15 and means for rotating the said rod.

2. A periodically acting spark-producing device for use in connection with toys, comprising, in combination, a sparking-rod having at one end a chisel-like configuration, a piece of cerium-iron 50 arranged co-axially with said rod opposite said chisel-like end of the same, a helical spring encompassing the rod and being connected with it at one end, means for holding said spring at its other end, and means for rotating the said rod.

3. A periodically acting spark-producing device for use in connection with toys, comprising, in combination, a sparking-rod having at one end a chisel-like configuration, a piece of cerium-iron 55 arranged co-axially with said rod opposite said chisel-like end of the same, a helical spring encompassing the rod and being connected with it at one end, a stationary member connected with the other end of said spring, the inner diameter 60 of the spring portion between said stationary member and the connected end being larger than the outer diameter of the said rod, and means for rotating the rod, substantially as set forth.

4. A periodically acting spark-producing device for use in connection with toys, comprising, 70 in combination, a sparking rod, a piece of cerium-iron arranged co-axially with said rod, means for pressing the rod against said piece of cerium-iron, a pinion secured to the rod, a crown-wheel 75 having teeth only on a part of its circumference, and being so arranged relatively to said pinion

as to be able to mesh therewith intermittently, and means for rotating said crown-wheel.

5. A periodically acting spark-producing device for use in connection with toys, comprising, in combination, a sparking rod, a piece of cerium-iron arranged co-axially with said rod, means for pressing the rod against said piece of cerium-iron, a pinion secured to the rod, a crown-wheel 10 having teeth only on a part of its circumference, and being so arranged relatively to said pinion as to be able to mesh therewith intermittently, another crown-wheel having likewise teeth only on a part of its circumference, running wheels supporting the device, motion-transmitting wheels between the latter crown-wheel and said running-wheels, and means for operating the device by 15 rotating said two crown-wheels, substantially as set forth.

6. A periodically acting spark-producing device for use in connection with toys, comprising, 20 a rotatable abrasive member, a piece of stone in contact therewith, a pinion connected to the member, a mutilated gear meshing with the pinion, a motor driving said gear, and an auxiliary spring operatively connected to the member, the 25 direction of winding of the auxiliary spring being such that the auxiliary spring is wound up or tightened during rotation of the member by the mutilated gear and is released and abruptly unwound when the mutilation in the gear reaches the pinion, the normal forward movement of the member failing to produce sparks, but the abrupt backward movement of the member upon release of the auxiliary spring causing a shower of 30 sparks.

7. A periodically acting spark-producing device for use in connection with toys, comprising, 35 a sparking rod having an abrasive end, a piece of stone, the abrasive end of the rod pressing against the stone, a pinion mounted on the rod, a mutilated gear meshing with the pinion, a motor for driving said gear, and an auxiliary spring functionally connected to the rod, the direction of winding of the auxiliary spring being such that the auxiliary spring is wound up or 40 tightened during rotation of the rod by the mutilated gear and is released and abruptly unwound when the mutilation in the gear reaches the pinion.

8. A periodically acting spark-producing device for use in connection with toys wherein sparks are to be produced at the end of a slender elongated member, comprising a sparking rod 45 having a chisel-shaped end, a piece of stone arranged coaxially with the rod, the chisel end of the rod pressing against the stone, a pinion mounted on the rod, a mutilated gear meshing with the pinion, a spring motor for driving said gear, and an auxiliary spring coiled about the rod and having one end stationarily mounted, 50 with the other end connected to the rod, the direction of winding of the auxiliary spring being such that the auxiliary spring is wound up or tightened during rotation of the rod by the mutilated gear and is released and abruptly unwound when the mutilation in the gear reaches the pinion, the smooth normal forward movement of the rod failing to produce sparks, but the abrupt backward movement of the rod upon 55 release of the auxiliary spring causing a shower 60 of sparks.

9. A periodically acting spark-producing device for use in connection with toys, comprising, 65 a rotatable abrasive member, a piece of stone in contact therewith, a pinion mounted on the 70

member, a mutilated gear meshing with the pinion, a motor for driving said gear, and an auxiliary spring coiled about a rod connected to the abrasive member, one end of the spring being 5 stationarily mounted and the other end being connected to the rod, the direction of winding of the auxiliary spring being such that the auxiliary spring is wound up or tightened during rotation of the member by the mutilated gear and 10 is released and abruptly unwound when the mutilation in the gear reaches the pinion, the coils of most of the auxiliary spring being larger in diameter than the rod but at least a few coils at one end of the spring being wrapped snugly 15 about the rod, the said closely wrapped convolutions functioning as a self-tightening frictional connection between the spring and the rod.

10. A periodically acting spark-producing device for use in connection with toys, comprising 20 a sparking rod having a chisel-shaped end, a piece of stone arranged coaxially with the rod, the chisel end of the rod pressing against the stone, a pinion mounted on the rod, a mutilated gear meshing with the pinion, a spring 25 motor for driving said gear, and an auxiliary spring coiled about the rod and having one end stationarily mounted, with the other end connected to the rod, the direction of winding of the auxiliary 30 spring being such that the auxiliary spring is wound up or tightened during rotation of the rod by the mutilated gear and is released and abruptly unwound when the mutilation in the gear reaches the pinion, the normal forward movement of the rod failing to produce sparks, 35 but the abrupt backward movement of the rod upon release of the auxiliary spring causing a shower of sparks, the coils of most of the auxiliary spring being larger in diameter than the rod but at least a few coils at one end of the 40 spring being wrapped snugly about the rod, the said closely wrapped convolutions functioning as a self-tightening frictional connection between the spring and the rod.

11. A periodically acting spark-producing and 45 traveling device for use in connection with toys, comprising an intermittent sparking mechanism, a motor for driving the same, traction wheels on which the device is supported and runs, a train of gearing connecting the aforesaid motor to the 50 traction wheels, means to make the traveling movement of the toy intermittent, said means and the spark-producing mechanism being so related to one another that the device dwells or ceases traveling movement at the moment that 55 the sparking mechanism produces a flash of sparks.

12. A periodically acting spark-producing and traveling device for use in connection with toys, comprising a rotatable abrasive member, a piece 60 of stone in contact therewith, a pinion mounted on the member, a mutilated gear meshing with the pinion, a motor for driving said gear, and an auxiliary spring operatively connected to the member, the direction of winding of the auxiliary 65 spring being such that the auxiliary spring is wound up or tightened during rotation of the member by the mutilated gear and is released and abruptly unwound when the mutilation in the gear reaches the pinion, traction wheels on which 70 the device is supported and runs, a train of step-up gearing connecting the aforesaid motor to the traction wheels, a gear in said train being mutilated to make the traveling movement of the toy intermittent, the mutilation of the said 75 gear and the mutilation of the aforesaid gear in

the spark-producing mechanism being so related to one another that the device dwells or ceases traveling movement at the moment that the sparking mechanism produces a flash of sparks.

13. A periodically acting spark-producing and traveling device for use in connection with toys, comprising a sparking rod having an abrasive end, a piece of stone arranged coaxially with the rod, the abrasive end of the rod pressing against the stone, a pinion mounted on the rod, a mutilated gear meshing with the pinion, a motor for driving said gear, and an auxiliary spring coiled about the rod and having one end stationarily mounted, with the other end connected to the rod, the direction of winding of the auxiliary 10 spring being such that the auxiliary spring is wound up or tightened during rotation of the rod by the mutilated gear and is released and abruptly unwound when the mutilation in the gear reaches the pinion, the smooth normal forward movement of the rod failing to produce sparks, but the abrupt backward movement of the rod upon release of the auxiliary spring causing a shower of sparks, traction wheels on which the device is supported and runs, and a train of 15 gearing connecting the aforesaid motor to the traction wheels.

14. A periodically acting spark-producing and traveling device for use in connection with toys, comprising a sparking rod having an abrasive end, a piece of stone arranged coaxially with the rod, the abrasive end of the rod pressing against the stone, a pinion mounted on the rod, a mutilated gear meshing with the pinion, a spring 20 motor for driving said gear, and an auxiliary 25 spring coiled about the rod and having one end stationarily mounted, with the other end connected to the rod, the direction of winding of the auxiliary 30 spring being such that the auxiliary spring is wound up or tightened during rotation of the rod by the mutilated gear and is released and abruptly unwound when the mutilation in the gear reaches the pinion, traction wheels on which the device is supported and runs, a train of step-up gearing connecting the aforesaid 35 motor to the traction wheels, a gear in said train being mutilated to make the traveling movement of the toy intermittent, the mutilation of the said gear and the mutilation of the aforesaid gear in the spark-producing mechanism being so related to one another that the device dwells or ceases traveling movement at the moment that the sparkling mechanism produces a flash of sparks.

15. A periodically acting spark-producing and traveling device for use in connection with toys, comprising a sparking rod having an abrasive end, a piece of stone arranged coaxially with the rod, the abrasive end of the rod pressing against the stone, a pinion mounted on the rod, a mutilated gear meshing with the pinion, a spring 60 motor for driving said gear, and an auxiliary spring coiled about the rod and having one end stationarily mounted, with the other end connected to the rod, the direction of winding of the auxiliary 65 spring being such that the auxiliary spring is wound up or tightened during rotation of the rod by the mutilated gear and is released and abruptly unwound when the mutilation in the gear reaches the pinion, the coils of most of the auxiliary spring being larger in diameter than the rod but at least a few coils at one end of the spring being wrapped snugly about the 70 rod, the said closely wrapped convolutions functioning as a self-tightening frictional connection 75

- tion between the spring and the rod, traction wheels on which the device is supported and runs, a train of step-up gearing connecting the aforesaid spring motor to the traction wheels, a gear in said train being mutilated to make the traveling movement of the toy intermittent, the mutilation of the said gear and the mutilation
- 5

of the aforesaid gear in the spark-producing mechanism being so related to one another that the device dwells or ceases traveling movement at the moment that the sparking mechanism produces a flash of sparks.

GEORG EINFALT.
